UNITED STATES PATENT OFFICE.

ALBERT C. GRUNWALD, OF RIVER FOREST, ILLINOIS.

CONTAINER.

Application filed December 6, 1922. Serial No. 605,173.

My invention relates to containers and more specifically to certain improvements in the neck and closure elements of containers of the type commonly employed to hold liquids or semi-liquids. Generally speaking, it is the object of my invention to so construct the neck and closure elements that they co-operate to insure and maintain an exceptionally tight seal when the closure element is positioned within and crimped upon the neck in the manner hereinafter described.

In the accompanying drawings illustrating my invention:

Figure 1 is a fragmentary view, partly in section, of a sheet metal container embodying the neck and closure element constructed in accordance with my present invention, this view illustrating the closure and neck as they appear prior to the application of the former to the latter;

Figure 2 is a similar view showing the closure fitted within and crimped upon the neck; and

Figures 3 and 4 are views corresponding respectively to the preceding figures, but illustrating a modified embodiment of my invention.

Similar characters of reference refer to similar parts throughout the several views.

Referring to Figures 1 and 2 of the drawing, reference letter A may be regarded as designating a can or container of the general type in which varnish and other liquid and semi-liquid products are commonly sold.

The can or container A is provided with a neck or spout B adapted to co-operate with a closure C.

The neck or spout B is formed from a single piece of metal and comprises the tapered lower portion 1, the annular internal horizontal shoulder 2, which constitutes one closure-seat, the annular vertical surface 3, which constitutes a second closure-seat, and the external bead 4, which constitutes a third closure-seat and which also co-operates with the closure to hold the latter firmly upon and against the other closure-seats. The said neck or spout B is attached to the container in any suitable manner, as, for instance, by solder.

The closure C is also formed from a single piece of metal and comprises the circular bottom 5, the annular vertical wall 6 and an outwardly and downwardly turned flange 7. The external diameter of the annular wall 6 of the closure is preferably about .002

of an inch greater than the internal diameter of the annular wall 3 of the neck. In applying the closure to the neck, the portions 5 and 6 of the closure are forced down within the wall 3 of the neck until the bottom 5 bears tightly against the annular shoulder 2. When this has been accomplished, the closure flange 7 overlies the bead 4. Now, with the bottom held tightly against the shoulder 2, there being a tight forced fit between the walls 3 and 6, the flange 7 is turned tightly under the bead 4, as illustrated in Figure 2. The act of turning the flange 7 under the bead not only causes the said flange tightly to engage the bead, but also pulls the wall 6 into even tighter engagement with the neck wall 3. After the flange 7 has been turned under the bead 4, as just explained, displacement of the bottom 5 from the shoulder 2 is prevented, firstly, by the engagement of the flange under the bead, and secondly, by the frictional fit between the walls 3 and 6 of the neck and closure, respectively. The wall 6, by its co-operation with wall 3, facilitates the application of the closure by centering the flange 7 with respect to the bead 4. The shoulder 2 also facilitates the application of the closure by insuring that both plate 5 and the lower edge of flange 7 will lie in planes at right angles to the axis of the neck before the crimping operation is effected.

In Figures 3 and 4 I have illustrated a modified construction, which is characterized by the fact that the bead 4 of the neck, while having a curved upper margin 4^a, is conformed to provide the conical lower surface 4^b. This style of bead may be formed as readily as the corresponding bead of Figures 1 and 2. Moreover, it facilitates the crimping operation incidental to the application of the closure and moreover insures a highly satisfactory seal. The engagement between the closure flange 7 and conical surface 4^a effectively tends to prevent outward movement of the closure with respect to the neck, but if any small amount of such movement should occur, the wedge action between the surface 4^a and the portion of flange 7 which lies thereagainst tends to draw the wall 6 into tighter engagement with the surface 3 and thus preserves a perfect seal.

By reason of the construction and arrangement of parts herein described, I am enabled to secure and indefinitely to main-

tain a seal which is far superior to the seals accomplished by crimped-on closures of the several types heretofore employed.

What I claim is new and desire to secure by Letters Patent of the United States is:

1. In a closure for containers, the combination of a sheet metal spout extending from said container having its outer end crimped to form an external annular shoulder, and having an internal annular shoulder spaced from its end, with a sheet metal cap, having a cup shape of slightly larger diameter than said spout, said cap being forced into said spout to form a perfect metal seal and seat against said internal annular shoulder, and having its outer edge crimped over and below the edge of said spout to retain said cap on said spout.
2. In combination, a sheet metal container having a substantially flat top, a relatively small sheet metal spout rising from said flat top, said spout being expanded outwardly adjacent its upper portion to form an annular internal shoulder in said spout flat

across its entire width and with the plane thereof lying at right angles to the axis of said spout, the upper edge of said sheet metal spout being rolled outwardly to form a hollow bead, an annular closure surface between said shoulder and said bead, a one-piece sheet metal cap comprising a circular bottom resting against the aforesaid shoulder, an annular wall snugly fitting said annular closure surface, the annular wall of said sheet metal cap being originally constructed of slightly larger diameter than said annular closure surface whereby the sheet metal of said annular closure surface is expanded outwardly in the forced seating of said cap, and a continuous annular flange on said cap which is turned over and under said hollow bead, the sheet metal edge of the cap crimped under said bead forming an outer joint sealed at all points around the bead and securely locking the cap against upward displacement from the bead.

In witness whereof, I hereunto subscribe my name this 10th day of October, 1922.

ALBERT C. GRUNWALD.
